EXPANSIBLE FRAME AND SUPPORT

Leon J. Jagus, Chicago, Ill.

Application May 17, 1937, Serial No. 143,183

7 Claims. (Cl. 40—155)

My invention relates to sign or card frames and more particularly of an expandible type and it consists in the constructions, arrangements and combinations herein described and claimed.

5 It is an object of the invention to provide a frame in which paired side frame members are simultaneously moved to accommodate a card or sign of different sizes.

It is also an object of the invention to provide 10 a novel construction of equalizer for effecting movements of the frame pieces.

It is also an object of the invention to provide 15 a novel support for the frame, embodying a hinge joint permitting adjustment of the frame to various angles for better display of a card or sign.

Additional objects, advantages and features of 20 invention will be apparent from the following description, considered in conjunction with the accompanying drawings, wherein

25 Figure 1 is a perspective view of my frame.

Figure 2 is a plan view of the frame portion 30 thereof.

Figure 3 is a cross section on the line 3—3 of 35 Figure 2.

Figure 4 is a cross section on the line 4—4 of 40 Figure 2, enlarged.

Figure 5 is a view similar to Figure 2 illustrating 45 a modified form of the frame.

Figure 6 is a plan view of one of the equalizer 50 members employed in the modified form.

Figure 7 is a side elevation of a supporting 55 stand for use with either forms of the frames.

Figure 8 is an elevation of the hinge joint.

Figure 9 is a vertical sectional view thereof.

55 Figures 10 and 11 are cross sectional views through the slide members showing modifications of their formations.

There is illustrated in Figure 1 a stand 10 upon 60 which there is supported an adjustable frame 11 the sides of which are expandible as indicated in dotted lines.

The stand 10 includes a stem 12 which may be of any approved contour and length and upon the upper end there is welded or otherwise secured a 65 plate 13. The plate 13 affords mounting of the frame as will now be described.

The frame 11 comprises two pairs of channel-shaped bars 14—14 and 15—15, the pair 14—14 being arranged vertically to the bars 15—15. Respective pairs of bars are suitably spaced apart, 70 in parallel relation, but in contacting relation at their points of crossing as indicated at 16. At the several points 16, the bars are welded or otherwise secured to retain the bar elements in proper rigid relation. The plate 13 is of a width 75 to fit between the upright bars 14 and welded to the cross bars 15—15. Thus the bars 14—14 and 15—15 are rigidly supported upon the stem 12.

The bars 14—14 and 15—15 are of the same 80 dimensions and include inwardly directed flanges

17 for guidance of a slide bar 18, as will be described.

The frame 11 includes side and frame pieces 19—20 and 21—22 which are of U-shaped formation, as viewed in cross section, and secured 5 medially thereof is a spacer 23 the ends of which are bent at right angles, as at 24. The ends 24 are of a length greater than the walls 25 of the frame pieces, so as to project therebeyond, for a purpose as will presently appear. The spacer 10 members 23 are of lesser width than the frame pieces 19—22 and therefore a recess 26 is provided 15 between the spacers 23 and respective walls 25 for reception of a card or sign to be displayed. The ends 24 afford support or backing to the card 15 or sign.

The end frames 19—20 and the side frames 21—22 each have fixed thereto a slide bar 18, which is slidable in respective channel bars 14—14 and 15—15, and preferably the slide bars 20 18 are formed with a right angularly extended foot 27, adapted to seat flatly upon the inner face 25 of respective spacer members 23, and secured by welding or otherwise. Thus, the frame portions 19—20 and 21—22 are slidably retained and in order to restrict too free movements, each of the channel bars 14—14 and 15—15 has a friction 30 device 28. The friction device, in the present instance, comprises a leaf spring 29, the ends of which are anchored to the wall of respective bars, 35 and intermediate the length of the spring, it is bowed slightly so as to project through an aperture 30 formed in the wall for contact with the slide bars 18.

The plate 13 is apertured medially of the frame 35 and has a bolt 31 mounted therein extending transversely of the bars 14—14 and 15—15, the bolt being of a length projecting slightly beyond the bars on both sides and pivotally mounted on respective ends of the bolt, there is an actuator 40 arm 32. The ends of the bolt may be headed in any approved manner to retain the arms in position. Each arm 32 has oppositely disposed slots 33, beginning at a point adjacent the pivot bolt 45 31, extending longitudinally of the arm and terminating adjacent respective ends of the arm.

Each slide bar 18 has a headed pin 34, rigidly 50 fixed to the bar at a point opposite respective frame ends or sides, the pin being slidable throughout the length of the slot complementary thereto. Thus, movement of the end or side frames will be equalized in their opposite movements, and it will be noted that the actuator arms 55 32 may partake of a rotary movement of approximately 160 degrees, which would be the case when the frame ends or sides are moved to their greatest adjustment.

The frame portion 20 is slotted as at 35 to admit the stem 12 therethrough and obviously, 60

the frame 20 is free to move along the stem to its various adjusted positions.

In Figure 5 I have shown a frame constructed as before described with the omission of the 5 stand, and the provision of a different type of actuator arms. In the present instance, the frame will be suspended by chains 36 or similar suspension means.

The channel bars 37-38 are arranged as described in connection with the bars 14-15, and 10 across the back wall of the bars 37-37, a plate 39 is secured. The plate is apertured at its medial portion, for mounting of a pivot bolt 40, and upon respective ends of the bolt there is mounted an 15 actuator arm 41 and 42.

It will be noted that the channel bars 37 are of a lesser length than the bars 38 for the purpose of providing a rectangular frame, and therefore the actuator arms 41 and 42 are of lengths approximately that of their complementary channel 20 bars.

The actuator arms 41-42 have an ogee curvature and inwardly of each longitudinal edge thereof, slots 43 and 44 are formed extending parallel to the edges thereof. A pin 45 on the slide bars 18 associated with the end frame members 46 traverses the slot 43 while the pin 47 of the side frame members 48 follows the slot 44 of the arm 43. The actuator arms in this form only 30 make a rotative movement about their pivot bolt of approximately 30 degrees, the adjustment being accomplished by the sliding relation between the pins 45-45 and 47-47 within their respective slots.

35 In Figures 7 to 9, I have illustrated a form of support for the frames, permitting angular adjustment from the vertical to more readily display a card carried by the frame.

The stem 12' is shown as cylindrical and screw 40 threaded as at 49, for engagement in a threaded socket 50. The socket 50 is hingedly connected between a pair of ears 51, by a pintle 52. The ears 51 are formed as an integral part of a body member 53, the body having a threaded bore 54 45 for reception of a threaded stem 55 of the base 10.

From a consideration of Figure 9, it will be seen that the socket 50 is rounded at one corner as at 56, the diametrically opposite corner being right angularly formed as at 57 and abutting the 50 body member 53. Thus the socket may swing upon the pivot pin in but one direction from the vertical, as indicated by dotted lines in Figure 7.

Angular adjustment of the frame with respect to its base may be accomplished by unscrewing of 55 the stem 55, moving the socket upon its pivot to the point of adjustment and then screwing the stem 55 back into impingement with the base of the socket 50.

The channel and slide bars may have various 60 shapes, as viewed in cross section, and in Figures 10 and 11, I have shown modified forms thereof.

In Figure 10, the channel bar 58 is of triangular formation and the slide bar 59 is similarly shaped for sliding engagement therewith. In Figure 11, 65 the channel bar 60 is constructed as described in connection with Figures 2 and 5, but the slide bar 61 has an I-beam formation.

While I have shown and described preferred 70 forms of my invention this is by way of illustration only, and I consider as my own, all such modifications in structure as fairly fall within the scope of the appended claims.

I claim:—

1. An expandible frame for supporting a display card comprising frame sections, each section having a slide bar, a channel bar slidably receiving each slide bar, oscillatable arm members positioned outwardly of respective channel bars, each arm having a longitudinally extended slot adjacent its ends, and a pin on each slide bar movable throughout the length of respective complementary slots. 5

2. An expandible frame for supporting a display card comprising a frame of channel bars, the bars being arranged in parallel pairs, one pair being positioned in crossed relation to the other and rigidly secured, a slide bar within each channel bar, a frame section rigidly connected with each slide bar, oscillatable arms positioned outwardly of respective pairs of channel bars, each arm having a longitudinally extended slot adjacent the ends, and a pin on each slide bar 20 movable along respective complementary slots. 15

3. The structure of claim 2 wherein friction means between the channel and slide bars prevent undue sliding movement of the slide bars.

4. An expandible frame for supporting a display card comprising a frame of paired channel bars, one pair being positioned in crossed relation to the other and rigidly secured, a slide bar within each channel bar, a frame section rigidly connected with each slide bar, oscillatable arms positioned outwardly of respective pairs of channel bars, each arm having a substantially ogee curvature, each arm having a slot extending parallel to each longitudinal edge, and a pin on each slide bar movable along respective complementary slots. 30 35

5. An expandible frame for supporting a display card comprising a frame of paired channel bars, one pair being positioned in crossed relation to the other and rigidly secured, a standard connected with the frame for such support thereof, 40 a slide bar within each channel bar, a frame section rigidly connected upon the outer end of each slide bar, oscillatable arms for each pair of channel bars, pivoted medially of the frame, each arm having a longitudinally extended slot adjacent its 45 ends, and a pin on each slide bar positioned adjacent respective frame sections and movable along respective complementary slots.

6. An expandible frame for supporting display cards comprising a frame of paired channel bars, 50 one pair being positioned in crossed relation to the other and rigidly secured, a standard connected with the frame for support thereof, a slide bar within each channel bar, a frame section rigidly connected upon the outer end of each slide 55 bar, said frame sections being U-shaped in cross section, a spacer member secured medially in each section, of lesser width than the frame section defining recesses for seating engagement of cards, said spacer members having inwardly turned portions at the ends, oscillatable arms for each pair of channel bars pivoted medially of the frame, each arm having a longitudinally extended slot adjacent its ends, and a pin on each slide bar positioned adjacent respective frame sections and movable along respective complementary slots. 60 65

7. The structure of claim 6, in which the channel bars are provided with an opening and a spring member positioned in the opening in bearing contact with the slide bars. 70

LEON J. JAGUS.
